TRACTOR-MOUNTED LOADER

John F. Shumaker, Mount Pleasant, Iowa, assignor to
J. I. Case Company, Racine, Wis., a corporation of Wisconsin

Filed Nov. 12, 1963, Ser. No. 77,360

Term of patent 3½ years

(Cl. D14—3)

FIG. 4

FIG. 1 is a right-side elevational view of a tractor-mounted loader showing my new design.

FIG. 2 is a front elevational view thereof, with portions omitted for convenience of illustration.

FIG. 3 is a front perspective view thereof; and

FIG. 4 is a rear elevational view thereof.

The tractor fragmentarily shown in broken lines is included for illustrative purposes only.

I claim:

The ornamental design for a tractor-mounted loader, substantially as shown and described.
